United States Patent Office

Des. 187,684
Patented Apr. 12, 1960

187,684

BLENDER

Jon W. Hauser, St. Charles Township, Kane County, Ill.,
assignor to McGraw-Edison Company, Elgin, Ill., a
corporation of Delaware

Application February 6, 1959, Serial No. 54,482

Term of patent 14 years

(Cl. D89—1)

Fig. 4

Fig. 5

Figure 1 is a front perspective view of a blender showing my new design;

Figure 2 is a rear perspective view;

Figure 3 is a fragmentary front elevational view;

Figure 4 is a view showing a longitudinal section taken on the line 4-4 of Figure 3; and

Figure 5 is a view showing a fragmentary cross-section taken on the line 5-5 of Figure 3.

The dominant features of my design are shown in full lines on the drawing.

I claim:

The ornamental design for a blender, substantially as shown and described.
